2,063,895

JOINT FOR STRUCTURAL TOYS

Henry R. Mack, Philadelphia, Pa.

Application April 10, 1936, Serial No. 73,660

6 Claims.

(Cl. 46—28)

This invention relates to the art of structural toys, and is concerned primarily with the provision of a novel type of joint for detachably connecting together various structural parts.

5 In the patent to Mack, Number 1,973,536, dated September 11, 1934, for a "Structural toy," there is illustrated and described a structural toy in which the various elements are identified as being of a rectangular cross section. The main 10 structural elements are of a square tubular formation, while the joining members are of a solid construction, having a cross sectional shape, corresponding to that of the tubular members.

The present invention has in view, as its foremost objective, the provision of an improved manner of detachably connecting together the structural elements of the toy, so as to render the latter adapted to be formed into an almost infinite number of constructional designs.

20 In accordance with this invention, so called "joint" members are availed of, and these joint members are of a solid construction and comprise bars or rods, having a substantially square cross section. The invention proposes an arrangement in which the joint members cross one another, and this invention, therefore, has in view as a further objective, the provision, in a structural toy of the character above noted, a joint 25 consisting of joint members which have been cut away to provide for their crossing one another, and with which are associated tubular elements which include means for maintaining the assembled relation of the joint members.

Yet another objective in view is the provision, 30 in a structural toy of the type above noted, of joint members and tubular structural elements which are connected to each other, by a detachable fastening, which is characterized as including spring elements integrally formed with the tubular elements and cooperating with recesses 35 in the joint members.

To the end of maintaining the joint members in various assembled positions such as a crossing relationship, the tubular elements are provided 40 with an extension on one side thereof, and which extension is intended to over-lap the "cross" for the purpose noted.

This invention also contemplates an arrangement in which one of the tubular elements itself 45 may be assembled with one of the joint members, with the tubular element received in the cutaway recess of the joint member. To the end of maintaining such an assembled relationship, the tubular elements are provided with slots in their

sides, which cooperate with the extensions above noted on other tubular elements.

Inasmuch as a structural toy, of the type with which this invention is concerned, may include joints of a more complex nature than a "cross", 5 the invention has in view as a further object, the provision of a joint member which comprises a solid hub portion, formed with a cutaway recess as above noted, and from which hub portion radiate a plurality of solid projections for detachable connection with the tubular elements. Another joint member is intended for cooperation with this joint member, including the plurality of projections, and this second joint member will also have a cutaway recess to cooperate with the 10 recess first mentioned.

In order to provide for the maintenance of the assembled relationship between the joint members, the hub portion of the first joint member is provided with a slot which is disposed above the 20 said cutaway recess. This slot is designed to receive the extension on one of the tubular elements which may be affixed to the second joint element.

Various other more detailed objections and advantages, such as those associated with carrying out the above noted thoughts in a practical embodiment, will, in part become apparent, and in part be hereinafter stated, as the description of the invention proceeds.

30 The invention, therefore, comprises a joint for structural toys, made up of solid joint members and tubular structural elements. The joint members are provided with cutaway recesses to afford an interfitting relationship therebetween, while 35 tubular elements are formed with extensions which cooperate with the joint members in maintaining the assembled relationship of the latter. A detachable connection between the tubular elements and joint members is provided in the form 40 of spring clips, which are positioned integrally from the tubular elements and cooperate with recesses in the joint members. Certain of the joint members, as well as their tubular members 45 may be provided with slots for receiving the extensions on other tubular members.

For a full and more complete understanding of the invention, reference may be had to the following description and accompanying drawing 50 wherein:

Figure 1 is a perspective illustration, bringing out the relationship of the various joint and tubular elements by a somewhat exploded showing.

Figure 2 is a view somewhat similar to Figure 1, developing a modified type of joint arrangement.

Figure 3 is another perspective showing of one of the tubular elements per se.

5 Figure 4 is an enlarged fragmentary showing of one end of one of the structural elements, this view being taken as a section therethrough, and

10 Figure 5 is a transverse section taken about on the plane represented by the line 5—5 of Figure 3.

15 Referring now to the drawing, wherein like reference characters denote corresponding parts, a so-called "cross" joint is shown in Figure 1 as defined by a pair of joint members designated A 15 and B. These joint members A and B are of substantially identical construction, and only one of them needs be here described for the purpose of this description.

20 The joint member A is shown as comprising a main body portion 10, which is provided intermediate of its extremities with a cutaway recess 11, the recess 11 being defined by a bottom wall 12, which is approximately halfway between the opposite faces of the body portion 10, and end walls 25 13. Extending outwardly from each end of the main body portion 10 is a reduced shank portion 14, there being a shoulder at 15, between the shanks 14 and the main body portion 10. Each of the shanks 14 is provided with a truncated spherical recess at 16, there being a pair of these recesses on opposite faces of each of the shanks 14.

25 It is evident that when the joint members A and B are assembled with the bottom walls 12 of the recess 11 in engagement with each other, that a cross joint is provided which at no point is of a greater thickness than the thickness of one of the body portions 10.

30 Referring now more particularly to Figure 3, one of the tubular structural elements is there shown, and referred to generally by the reference character C. The element C is of a tubular formation, having a substantially square cross section, and is defined by side walls, designated 35 17, 18, 19 and 20 respectively. As shown in Figure 1, as well as Figure 3, the side wall 20 is continued with a reduced breadth, as an extension designated 21. At each end the metal of the side walls 17 and 19 is partially cut away to provide 40 leaf spring members 22, which are integrally connected with their respective side walls, as shown at 23. The metal of each of the spring members 22 is deformed, as indicated at 24, to provide an interiorly extending projection 25 that is intended 45 to be substantially complementary to the recess 16, being designed to fit therein.

50 With the joint members A and B in the cooperating relationship brought out by Figure 1, one of the structural elements C is now positioned 55 so that the shank 14, on the element B is received in the hollow of the tubular element C. In this position the leaf springs 22 are effective through the engagement of the projections 25 with the recesses 16, to detachably establish the connection 60 between the element C and the joint members B.

65 In this position, the extension 21 overlies the body portion 10 of the joint member A to prevent disassembly of the parts. The joint member C 70 may be positioned over one of the shanks 14 with a joint member A, in which event the extension 21 on this tubular element C will overlie the body portion 10 of the joint member B, to further strengthen the connection with the above described arrangement.

75 It is apparent that each of the joint members A and B have a shank 14 which is designed to have one end of one of the structural members C detachably connected thereto, but with the extension 21 already overlying the joint members A and B, the structural element so positioned should not have the extensions 21 on the ends which receive the shanks 14.

80 As shown in Figure 3, the side walls 17 and 19 are provided with slots 26, which may be enlarged 10 as shown at 27 for a purpose ultra to this invention. This makes possible the positioning of one of the tubular elements C, with either of the side walls 18 or 20 engaging the bottom wall 12 of one of the joint members A and B. In this position, the slots 27 are adapted to receive an extension 21 on another tubular element C, which may be positioned over the shank 14.

85 Referring now more particularly to Figure 2, a somewhat modified form of joint member is 20 shown and referred to generally by the reference character D. This joint member D is illustrated as comprising a main hub portion 28, which is formed with a recess 29, which is similar to the recess 11 above described.

90 Just above the recess 29, the hub portion 28 is provided with a slot 30. Extending radially outwardly from the hub portion 28 are a plurality of 30 projections 31, which correspond to the shanks 14 of the joint members already described. In the illustrated embodiment, the hub member 28 is shown as provided with three of these extensions 31, but obviously the invention is not to be limited in this respect, as this number could be varied as occasion demands. Each of the shanks 35 31 is formed with depressions 32 on opposed faces, and which depressions correspond to depressions 16 in the shanks 14.

95 The joint member D is designed for cooperation 40 with one of the joint members A or B. As shown in Figure 2, the joint member A is to be positioned so that the bottom wall 12 of the recess 11 therein engages the bottom wall of the recess 29, so that when one of the tubular elements C is positioned to receive the shank 14 of the joint member A, the extension 21 will enter the slot 30 to maintain the joint members A and B in assembled 45 relationship.

100 In a manner already described, another tubular element C may be positioned over the lowermost of the extensions 31, in which event the extension 21 will overlie the main body portion 10 of joint member A, to further strengthen the connection.

105 It is evident from the foregoing that a joint for structural toys is provided, which is characterized by the quick detachability of the various parts, as well as a positive assurance that the joints will be maintained in their assembled relationship until the occasion arises when it is desired to disassemble the same. Moreover, a good detachable connection between each of the tubular elements and the joint members is provided for.

110 A slight modification is shown in Figure 5, in which the leaf springs 22 are joined with 65 strengthening ribs 33. These ribs 33 extend lengthwise of the springs 22 and serve to impart rigidity thereto. They may be joined by a metal stamping operation.

115 While preferred specific embodiments of the invention are hereinbefore set forth, it is to be clearly understood that I am not to be limited to the exact constructions illustrated and described, because various modifications of these 70 75

details may be provided in putting the invention into practice within the purview of the appended claims.

I claim:—

- 5 1. A joint of the character described comprising a joint member formed with a recess and a shank at one side of the recess, said recess being adapted to receive a member which is to be joined to the joint member, a tubular element including means cooperating with the shank for detachably connecting the tubular element to the shank, and an extension on the tubular element to overlie the recess and thereby engage a member which may be disposed in the recess to maintain the 10 assembled relationship between the last mentioned member and the joint member.
- 15 2. A joint of the character described comprising a joint member consisting of a central body portion formed with a recess and a shank extending from each side of said body portion, each of said shanks being formed with depressions therein, a tubular element adapted to receive one of said shanks, said tubular element being formed with springs which cooperate with the depressions in the shank to establish a detachable connection, and an extension on said tubular member adapted to overlie the said recess.
- 20 3. A joint of the character described comprising a joint member formed with a recess and a shank at one side of the recess, a second joint member formed with a hub portion having a recess complementary to the recess in the first mentioned joint member, there being a slot in said hub portion above said recess, a plurality of projections extending outwardly from said hub portion, and a tubular element on one of said projections, said tubular element being formed with an extension overlying the first mentioned joint member, and a second tubular element on the shank of said first mentioned joint member, said second tubular member having an extension 25
- 30 35 40

which is received in the slot in the hub portion of the second joint member.

4. A joint of the character described comprising a joint member formed with a recess and a shank at one side of the recess, a second joint member formed with a hub portion having a recess complementary to the recess in the first mentioned joint member, there being a slot in said hub portion above said recess, a plurality of projections extending outwardly from said hub portion, and a tubular element on one of said projections, said tubular element being formed with an extension overlying the first mentioned joint member, and a second tubular element on the shank of said first mentioned joint member, said second tubular member having an extension 10 15 20 25

5. A joint of the character described comprising a joint member formed with a shank, there being a depression in one face of the shank, a tubular element receiving said shank, said tubular element having a leaf spring integrally formed with one side of the tubular element, said leaf spring having a projection adapted to enter the recess on the shank.

6. A joint of the character described comprising a joint member having a main body portion and a reduced shank extending therefrom, said shank being formed with depressions on opposed faces thereof, a tubular element received on said shank and formed with a pair of leaf springs on 30 35 opposite faces, said leaf springs being cut from the metal of the tubular element and formed with projections adapted to engage said depressions to establish a detachable connection between the joint member and a tubular element. 40
